JP 897850 5/1994

1 Claim, 4 Drawing Sheets

FIG. 1 is a perspective view of the top, front and right side of a ball-point pen showing our new design;
FIG. 2 is a front elevational view thereof;
FIG. 3 is a left side elevational view thereof;
FIG. 4 is a right side elevational view thereof;
FIG. 5 is a rear elevational view thereof;
FIG. 6 is a top plan view thereof;
FIG. 7 is a bottom plan view thereof;
FIG. 8 is a front elevational view of the body thereof;
FIG. 9 is a left side elevational view of the body thereof;
FIG. 10 is a right side elevational view of the body thereof;
FIG. 11 is a rear elevational view of the body thereof;
FIG. 12 is a top plan view of the body thereof;
FIG. 13 is a bottom plan view of the body thereof;
FIG. 14 is a front elevational view of the cap thereof;
FIG. 15 is a left side elevational view of the cap, the right side being a mirror image thereof;
FIG. 16 is a rear elevational view of the cap thereof;
FIG. 17 is a top plan view of the cap thereof; and,
FIG. 18 is a bottom plan view of the cap thereof.
